UNITED STATES PATENT OFFICE.

FRANK W. ADSIT, OF CHICAGO, ILLINOIS.

INTERCOMMUNICATING TELEPHONE LOCKOUT SYSTEM.

1,307,651.

Specification of Letters Patent. Patented June 24, 1919.

Application filed July 29, 1916. Serial No. 112,150.

To all whom it may concern:

Be it known that I, FRANK W. ADSIT, a citizen of the United States, residing at Chicago, in the county of Cook and State 5 of Illinois, have invented certain new and useful Improvements in Intercommunicating Telephone Lockout Systems, of which the following is a specification.

My invention relates more particularly to 10 providing means where one subscriber on a telephone party line connected with a central station may call any other subscriber on that line, or the central station, and hold a private conversation with the party so called, 15 the remaining parties on the line being locked out.

This invention is more or less closely related to my two co-pending applications Serial Nos. 30,166, and 15,114, and in the specification and drawings I show parts of circuits and devices covered in these two, and also a device similar to the one covered in my co-pending application Serial #57,310, but this invention is materially different 25 from any of these cases, both in the manner in which the power is supplied for making selections and ringing the bells, and also in numerous important details required in the operation of the system.

30 While it is necessary to show some circuits and devices covered in the other cases, these are not a part of this invention and are not set up in claims herein, the claims covering only the improvements developed 35 in this particular invention.

One object of my invention is to provide in a telephone lockout system a source of selecting and ringing current at the central station and means at each of the subscribers' 40 stations for applying such current to the line.

Another object of my invention is to provide in a telephone lockout system means for calling more than one party on a party line at the same time, allowing both parties 45 to enter in on the line, but locking out the remaining parties.

Another object of my invention is to provide means for limiting the length of conversation on a telephone lockout party line, and means for clearing or restoring the line to normal at the end of any given predetermined period.

With these and incidental objects in view 50 the invention consists of certain novel fea-

tures of construction and combination of parts, the essential elements of which are hereinafter described with reference to the drawings which accompany and form a part of this specification.

In the drawings is disclosed a party line embodying my invention, Figure 1 showing the central office circuit and one of the subscribers' circuits, and Fig. 2 showing two of the subscribers' circuits.

For easy reference similar parts and similar wires at station "A", "B" and "C" are denoted by the same numerals with the symbol (') added at station "B" and symbol (") added at station "C".

Similar parts and wires at the exchange or station "D" are denoted by different numerals where there are considerable differences in the operation of the central apparatus.

The ground connections at the stations "A", "B" and "C" are denoted by letters "G", "G'" and "G\"", respectively, while grounds at the central station, which would in fact be one ground, are shown as "H", "H'", "H'" and "H'" for easy reference in the circuit.

The arrangement of circuits and apparatus in my invention is such that it may be embodied in the form of an attachment that can be added to the common type of magneto telephone, although a complete instrument embodying the device may also be manufactured.

It will be noted from the drawings that the magneto ordinarily used in a local battery telephone is dispensed with, but the circuit otherwise is that commonly known as the magneto telephone circuit.

Subscriber's station apparatus.

The three subscribers' stations "A", "B" and "C" and the central station "D" are connected by line wires "E" and "F" and the ground connections "G" and "H", which of course may be omitted and a third wire substituted therefor.

The subscribers' apparatus consists, in addition to the ordinary equipment of a magneto type telephone, of a selecting dial 11 having buttons from 1 to 10, half of the dial being broken away in the drawing.

These buttons 1 to 10, slidably mounted in any suitable manner in the dial 11, are adapted to make contact with the spring 12

when depressed, as the spring is rotated, but to clear the spring and make no electrical connection when they are not depressed.

The spring 12 is carried by the insulated pointer 13 on the shaft 14, which in turn is driven by the ratchet wheel 15 actuated by the dog 16 carried by the armature 17, which in turn is actuated by the motor coils 18, the motor coils preferably being polarized by the permanent magnet 19, so as to respond to alternating current, which will step all ratchet wheels in synchronism with its own frequency.

The spring 20 fastened to the shaft and the frame of the attachment in any suitable manner serves to return the ratchet wheel to its normal position when released from actuation of the dog.

Any type of retaining pawl, which would be controlled by the release lever in the same manner as is the pawl 16, may be utilized to hold the ratchet wheel 15 during the backward travel of the pawl 16, or the inertia of the wheel 15 may be depended upon.

A starting coil 21 controlling the latch 22 is adapted to unlatch both of the levers 23 and 24 actuating the bank of springs associated with each of these levers, while a selecting coil 25 is adapted to unlatch the lever 24 only and actuate the bank of springs associated with that lever.

A restoring coil 26 through its armature 27 and the link 28 is adapted to restore the ratchet wheel 15, and also restore the levers 23 and 24 when the restoring coil 26 is actuated by direct current which is supplied at the proper time, as will be hereinafter described.

A restoring relay 29 serves by the contact 30 to supply current to the restoring coil when the restoring circuit is applied.

The ratchet wheel 15 carries thereon a pin 31 adapted to make contact with the spring 32 in its final position, and carries also an insulating button 33, which on the first step of the ratchet wheel allows the opening of the bank of normal contact of springs associated therewith.

The shaft 14 carries a selecting pointer 34 adapted to make contact during its revolution with the selecting spring 35, and this contact pointer 34 is set differently in each of the subscribers' instruments, so that contact between the pointer 34 and the selecting spring 35 will be made at only one instrument at any one time while the pointer 13 carrying the spring 12 is in the same position on the shafts of all attachments and contact can be made at any desired time in the revolution of the wheel 15 by depressing the proper button.

The fundamental idea of selection is that to call a party, number 3, for instance, the act of depressing button number 3 will cause a contact to be made between the spring

12 and the button 3 at the station where the call is initiated at the same instant that the contact between the selecting pointer 34 and the selecting spring 35 is made at the called station, completing a circuit that will be 70 traced hereinafter.

The alternating current used in operating the motor coils 18 and also to ring the bell 36 is supplied from the central station "D" in a manner hereinafter explained, whenever 75 the contact 37 is closed and, as is evident, this contact would preferably be closed by the act of depressing any of the buttons, and it is merely shown as a conventional contact for ease in tracing the circuits.

Means are provided at the central station "D" for restoring line conditions to normal at any time that a ground is placed on the line "F" in any manner, either at central station "D" or any of the subscribers' stations when the timer is in service, and the line may also be restored by the completion of a local circuit at the central station "D" to be taken up in its turn, and an emergency contact 38 is provided at each station so 80 that a subscriber at any station may clear the line at any time, whether locked out or not, in case of an emergency, but as this contact is only for emergency purposes it is preferably covered by a seal or glass, so 85 that it could not be used without its use being known.

The subscriber's talking set 39 is of the ordinary local battery type and is normally cut off of the line, being switched in on to 100 the line only when calls are made or received.

Subscriber's station circuit operation.

When subscriber "A" wishes to talk with subscriber "B" at station 3, he depresses button 3 and contact 37, which may be one act, thus placing alternating current on the line "E" and "F" through the actuation of the coil 21, as described later.

The closing of the contact 37 actuates the starting coil 21, the circuit being as follows:

Local battery 50, wires 44, 45, 51, coil 21, wire 52, contact 53, wire 54, contact 37, wires 55, 56, 57, to the other side of the local battery 50, and the actuation of the coil 21 fulfills the starting conditions by placing the ground "G" on the line wire "F" through the following circuit:

From the ground "G", wires 58, 59, 60, 120 contact 61, wire 62, contact 63, wires 64, 48, 49 to the line wire "F".

Mechanism at central office is adapted to place alternating current on the line wires "E" and "F" when a ground is placed on the line "F", except under certain conditions of the timer.

The motor coils 18 on all stations are bridged across the line wires "E" and "F" and responding to the alternating current 130

step the ratchet wheel 15 around to the final position where the pin 31 makes contact with the spring 32.

The first step of the ratchet wheel opens 5 the contacts in the bank of springs controlled by the button 33.

The talking set of subscriber "A" is then 10 across the line wires "E" and "F" when the receiver is removed from the hook through the following circuit:

From line wire "E", wires 41, 42, condenser 43, through the talking set from the switch hook through wires 44, 45, contacts 46, 47, wires 48, 49, to the other line wire "F".

15 After the ratchet wheels have reached their final position, alternating current is removed from the line wires "E" and "F" by central office apparatus under conditions hereinafter described.

20 The circuit at station "B" has now been modified from that shown in the drawing, because the selecting coil 25' has been actuated by alternating current through a momentary closing of a circuit which includes 25 at station "B" the contact between the selecting pointer 34' and the selecting spring 35' at the same instant that the spring 12 made contact with the button 3 at station "A", the circuit being from line wire "F", 30 which carries one side of the alternating current through wires 49, 48, 64, contact 63, contact 65, wire 66, brush 67, spring 12, button 3, plate 11, wires 68, 58, to the ground "G" at station "A" through the earth to the 35 ground "G" at station "B", wires 58', 59', 69', selecting contact 34', selecting contact spring 35', wires 70', selecting coil 25', wires 71', 72', 73', 41', to the line wire "E" which carries the other side of the alternating current.

40 The bell 36' is also brought into circuit by the actuation of the coil 25', and in series with the condenser 43' is placed across the line wires "E" and "F", the circuit being as follows:

Line wire "E", wires 41', 42', condenser 43', wire 168', bell 36', wire 169', contact 47', wires 48', 49', to the line wire "F".

It will be noted that the back contact of 50 the switch hook is not used in the bell circuit, but this contact is used in placing a ground on the line wire "F" when the ratchet wheel 15' reaches its final position, the circuit being as follows:

55 Line wire "F", wires 49', 48', contacts 47', 46', wires 45', 44', switch hook 40', wire 170' to the final contact spring 32', pin 31', through the ratchet wheel 15', wires 69', 59', 58', to the ground at G'. The circuit in all 60 stations where the selecting coil 25 has been actuated may be traced in the same manner.

65 The energizing of the selecting coil 25' actuates the bank of springs associated therewith and cuts the talking set of subscriber "B" across the line, as already de-

scribed with respect to subscriber "A", but the starting coil 21' of subscriber "B" was not actuated, and hence the bank of springs associated therewith was not actuated as the contact 37' was not closed at station "B", 70 and the closing of this contact after the first step of the ratchet wheel 15' could not affect the circuits, as contacts 37' and 53' are in series, so that no subscriber could come in on the line after the first step had been taken by 75 the ratchet wheel 15, and hence all parties except the party initiating the call and the party or parties called are locked out, also the position of the buttons in all stations except the calling station cannot affect the 80 system as the starting coils 21 have not and cannot be energized.

Central station apparatus.

The selecting circuit for the central station "D" is similar and operates in a similar manner to that at stations "A", "B" and "C", except that additional functions are performed, also that the drop 74 takes the place of the bell 36 and the talking circuit 90 of the operator would of course be upon a cord circuit adapted to be connected with the jack 75 in the ordinary manner.

The central station apparatus includes in addition to the drop and jack and selective 95 means, similar to that at the subscriber's station, an alternating current control switch 100, actuating the bank of springs 101, a pole changer of ordinary construction 102, an alternating current switch control relay 100 103, a timing mechanism 104, including a tone test circuit 105 and three release coils 106, 107, 108 in parallel, the release coil 108 being similar to the release coils 26 in the subscribers' attachments.

105

Central station circuit operation.

The act of initiating a call at one of the stations, as heretofore described, places a ground on the line wire "F", and the placing of this ground on this line wire "F" when the timer is not in service actuates the alternating current switch relay 103, the circuit being as follows:

Central office battery 109, wires 110, 111, 112, contact 113, wire 114, coil 103, wire 115, contact 116, the ratchet wheels not having been stepped forwardly as the alternating current has not yet been applied, to the ground "H", from the ground "H" through 120 the earth to the ground at the subscriber's station initiating the call and through that station to the line wire "F", as already traced, from the line wire "F" at central station through wires 117, 118, 119, 120, 121, contact 122, wires 123 and 124, to the other side of the battery 109.

The closing of the contact 125 by the actuation of the coil 103 closes a circuit from the battery 109 through wires 110, 111, 112, 130

contact 113, wire 114, contact 125, wire 130, contact 129, wire 128, coil 127, wires 126, 120, 121, contact 122, wires 123, 124, to the other side of the battery 109 actuating 5 through the energizing of the coil 127 the armature 131, which actuates the quick acting switch link 132, and through it the bank of springs 101. The operation of the bank of springs places alternating current from 10 the main springs 133 and 134 of the pole changer 102 directly on the line wires "E" and "F".

With the first step of the ratchet wheel 15³, station "D", the bank of springs controlled by the insulated pin 33³ is actuated, which starts the timer mechanism under control of the periodic contact maker 135.

Just before the ratchet wheel 15³ reaches its final position the insulated pin 33³ will 20 close the contact 146, which actuates the coil 211, the circuit being as follows:

Alternating current from main spring 134 of the pole changer, wire 147, contact 148 now made, wire 166, contact 146, wire 25 149, coil 211, wire 150, contact 151, to the ground "H", from the ground at "H" through the earth to the ground at the station being called through the final contact and the back switch hook contact at the station back over the line "F" to the main spring 133 carrying the other side of the alternating current, and evidently this relay will remain actuated as long as a ground 30 remains on that side of the line, maintaining 35 the contact 152 open.

The ringing control relay 211 controls the quick acting armature 153 mounted on the main inertia controlled lever 154, so that when the armature 153 comes up at the first 40 impulse of current it is latched in the forward position by latch 155 and the inertia lever gradually comes up through the action of the spring 225 and maintains the contact 152 open, but unlatches the latch 45 155 so that when the coil 211 is finally de-energized both armature and lever may swing back to their normal position, as shown in Fig. 1.

While the ratchet wheel 15³ is rotating 50 synchronously with the ratchet wheels in the subscribers' instruments grounds made at any subscriber's instrument by the selecting contact will actuate the coil 167, the circuit being as follows:

55 Alternating current from the main spring 134, wires 156, 157, coil 167, wire 158, contact 159, wire 160, contact 161, to the ground "H", from the ground "H" through the earth to the ground at the subscriber's 60 instrument, where the selecting contact was made and back through that instrument over the line wire "F" to the main spring 133, which carries the other side of the alternating current, as already traced.

65 Therefore, the coil 167 will be actuated

once for each ground that is made by the selecting contact of any instrument prior to the time that the contact 159 is opened, which is the final position of the ratchet wheel 15³, and also will be actuated by the 70 closing of the final contact in one of the called instruments or the calling instrument, and as the ground then introduced remains until other circuit conditions hereinafter explained are established, hence it is not essential that the final contact of the attachments be all made at absolutely the same instant, but all must be made before contact 75 159 is opened or contact 172 closed.

The armature 162 through the dog 163 80 will cause the quadrant 164 to take one step for each actuation of the coil 167, and the first two steps of the equipment will not affect the circuit arrangements, but should a third step be taken, as when two or more 85 parties are called, the latch 165 will be unlatched and the ground "H" be opened from the main spring associated with latch 165, and there will be transferred to the main spring the timer controlled ground 90 "H".

The armature 162 associated with the coil 167 is preferably made of a sluggish responsive nature, so that it will be drawn up by alternating current but will not follow the 95 fluctuations thereof.

We have seen that alternating current has been placed on the line wires "E" and "F" through the actuation of the coil 127 and this alternating current is removed 100 after it has performed its function by the actuation of the coil 171.

It is apparent that the coil 171 cannot be actuated until the contact 152 is again closed, as contact 172 which controls coil 105 171 is in series with contact 152.

If only one party has been called and the quadrant 164 took only two steps so that the ground "H" would remain as shown in the drawing, the coil 211 will remain 110 actuated until all grounds are removed from the line wire "F," which would be accomplished when the switch hook of the party called was raised in answering his call, and the switch hook of the party calling was 115 also raised, the removal of the ground from the line wire "F" opening the circuit of the coil 211, as already traced, with the contact 152 closed and with the contact 172 closed in the final position of the ratchet 120 wheel 15³, the coil 171 would then be actuated, the circuit being as follows:

Battery 109, wires 110, 111, 112, contact 173, wires 174, 175, coil 171, wire 176, contact 172, wire 177, contact 152, wires 178, 125 179, contact 180, wires 123, 124, to the other side of the battery 109, restoring the bank of springs 101 to the condition shown in the drawing and cutting off the battery 109 from the coil 171 through contacts 180, 173, 130

and the parties would then talk in the usual manner.

Timer operation.

5 It has been shown that the timer motor coil 137 is started as soon as the call is initiated and begins to time the length of conversation.

10 Pins are provided, carried by the ratchet wheel 145, for changing certain conditions in the timer service as follows:

When pin 181 moves one end of the lever 182 the contact 183 is opened, which removes the ground "H²," which had taken the place 15 of the ground "H" in the circuit holding the coil 211 if three steps were taken on the quadrant 164, which would have been done if more than one party was called by the party initiating the call depressing more 20 than one button.

It is therefore seen that in case more than one party was called the coil 211 would remain actuated until the contact 183 was opened by the movement of the lever 182 25 by the pin 181, so that for the length of time taken for the pin 181 to reach the lever 182 the bells of the called parties would be rung and the alternating current could not be removed from the line by one party answering sooner than the other, but would 30 be removed at the expiration of this time regardless of grounds on the line.

Hence if one of the parties did not answer the ringing current would remain on the 35 line, but this would be relieved by the actuation of the lever 182, and at the end of the period taken for the pin to actuate lever 182, the ringing current would be removed and the line put in talking condition.

40 When the pin 184 strikes the lever 182 the spring resting thereon will be cammed still farther upwardly and make contact with the spring 185, grounded at "H²," which brings this ground through wires 45 186, 187, through the timer relay 188, wires 189, 190, 110 to the battery 109, and as the other side of this battery is connected to line "F" through wires 124, 123, contact 122, wires 121, 120, 119, 118, 117, it is evident that a ground now placed on the line 50 "F" will actuate the coil 188.

If either of the parties talking hangs his receiver upon the hook, thus closing his back contact, the ground will be placed upon 55 the line wire "F" through the final contact of the ratchet wheel, as already traced, and as coil 188 will be actuated the entire system will be restored to its normal condition through the potentiation of the following 60 circuits:

Restoring of subscribers' attachments.

Battery 109, through wire 124, 123, contact 122, wires 121, 120, 119, 118, 117, to line 65 wire "F" and from the other side of battery

109 through wires 110, 190, 191, contact 192, wires 193, 194, 81, to line wire "E," this battery actuating all of the restoring mechanism in the attachments, as already described.

Restoring of central apparatus.

70

Battery 109, wires 110, 190, 191, contact 195, wire 196, contact 197, wire 198, to one side of coils 106, 107, 108, and from the other side of battery 109 through wires 124, 145, 75 199, to the other side of coil 106, from the junction of wires 145, 199, through wire 200, to the other side of coil 108, and from the junction of wires 124, 145, to the other side of coil 107.

The actuation of coil 106 removes the dogs from the ratchet wheel 145 of the timer, and allows the wheel to be returned to its normal condition by a suitable spring, not shown, restores the latch associated with coil 188 and the contacts associated therewith, and the returning of the ratchet wheel 145 restores the lever 182 and the contact associated therewith to its normal condition.

The actuation of coil 107 returns the quadrant 90 164 and the latch and springs associated therewith to their normal condition, while the actuation of coil 108 removes the dogs from ratchet wheel 15³ allowing it to be returned to its normal condition, and thus 95 restoring the contacts associated therewith to their normal condition, resets the latch of the selecting coil 25³ to its normal condition and also the contact associated therewith.

The contact 139 is opened by the returning 100 of ratchet wheel 15³ so that the circuit through which the interrupted contact maker was actuating coil 137 is now opened and the timer remains in its normal condition until again actuated.

Should neither party hang up for a considerable period of time the pin 202 is adapted to restore the line to normal, even though 105 neither of the parties hang up.

This is accomplished by the following 110 circuit:

Battery 109, wires 110, 190, 189, coil 188, wires 187, 186, 203, ratchet wheel 145, pin 202, spring 204, wires 205, 200, 145, 124, to the other side of the battery, the effect of 115 the actuation of the coil 188 having already been explained.

The pin 202 will make contact with spring 206 a few seconds before it makes contact with spring 204, closing the primary of the tone test circuit 105 sending a tone out on the line wires to advise the talking subscribers that their time limit will soon have expired, the secondary of the coil being of high impedance and permanently bridged 120 on the line. If the key 142 is thrown from the normal position to the one shown in the drawing, thus opening contact 141, the timer and all its functions will be inoperative, 125 while if the key is thrown in the other direc-

130

tion so as to close contact 207, the coil 188 will be actuated and the timer restored to normal, as heretofore described through the following circuit:

5. Battery 109, wires 110, 190, 189, coil 188, wires 187, 208, 209, contact 207, wires 210, 200, 145, 124, to the other side of the battery 109.

10. While I have described my invention and illustrated it in one particular design, I do not wish it understood that I limit myself to this construction, as it is evident that the application of my invention may be varied in many ways within the scope of the following claims.

15. Claims:

20. 1. In an intercommunicating telephone system the combination of a central station, multiple subscribers' stations, line wires connecting said subscribers' stations with said central station, a ground connection at each of said subscribers' stations and at said central station, means whereby selecting current may be impressed on said line wires at said central station, means at each of said subscribers' stations controlling the means at said central station for impressing selecting current on said line wires, electro-magnetic synchronously operated means at each of said subscribers' stations responsive to said selecting current, settable contacts at each of said subscribers' stations, fixed contacts at each of said subscribers' stations, both settable and fixed contacts being adapted to be made by said synchronously operated means whereby two or more of said subscribers' stations may be rendered operative with respect to said line wires.

25. 2. In an intercommunicating telephone system the combination of a central station, multiple subscribers' stations, a pair of line wires connecting said central station and said subscribers' stations, a ground connection at said central station and each of said subscribers' stations, means whereby a subscriber at one of said stations may impress selecting current from a source at central station on to said line wires for the purpose of calling one or more of said subscribers' stations, means at central station whereby said selecting current will be automatically removed from said line wires when a talking connection has been completed if only one of said subscribers' stations was called, and alternative means at said central station whereby the completion of a talking circuit will not remove said selecting current from said line wires until the expiration of a predetermined period.

30. 3. In an intercommunicating telephone system the combination of a central station, multiple subscribers' stations, a pair of line wires connecting said central station and said subscribers' stations, means at said central station for impressing selecting current

35. on said line wires, means at said central station for removing said selecting current from said line wires, and circuit changing means at said central station whereby said selecting current may be removed at a later period in the cycle of the completed call where more than one party has been called than when only one party has been called.

40. 4. In an intercommunicating telephone system the combination of a central station, multiple subscribers' stations, a pair of line wires connecting said central station and said subscribers' stations, a ground connection at said central station and at each of said subscribers' stations, means at said central station operable from each of said subscribers' stations for impressing selecting current on said line wires, means at said central station for removing said selecting current from said line wires after it has been so impressed, and means at each of said subscribers' stations for determining the time at which said selecting current will be removed from said line wires.

45. 5. In an intercommunicating telephone system the combination of a central station, multiple subscribers' stations, a pair of line wires connecting said central station and said subscribers' stations, a ground connection at said central station and each of said subscribers' stations, and means at said central station controllable at each of said subscribers' stations for impressing selecting current on each of said line wires for the purpose of selecting one or more of said subscribers' stations, means at said central station for removing said selecting current from said line wires, and means at each of said subscribers' stations for causing said selecting current to be removed upon the completion of the talking circuit between the calling and called subscribers' stations, and additional means at said subscribers' stations whereby said selecting current may be removed from said line wires at a predetermined period after the talking connection has been completed between a calling station and one called station.

50. 6. In an intercommunicating telephone system the combination of a central station, multiple subscribers' stations, talking sets at said subscribers' stations, selecting means at said subscribers' stations, line wires connecting said subscribers' stations with said central station, a ground connection at each of said subscribers' stations and said central station, means at said central station whereby selecting current may be impressed on said line wires at said central station, means at each of said subscribers' stations controlling said means at said central station for impressing selecting current on said line wires, electro-magnetic synchronously operated means at each of said subscribers' stations responsive to said selecting current,

settable contacts at each of said subscribers' stations, fixed contacts at each of said subscribers' stations, both settable and fixed contacts being adapted to be made by said 5 synchronously operated means whereby two or more of said subscribers' talking sets may be rendered operative with respect to said line wires.

7. In an intercommunicating telephone 10 system the combination of a central station, multiple subscribers' stations, a pair of line wires connecting said central station and said subscribers' stations, a ground connection at said central station and each of said 15 subscribers' stations, a source of selecting current at said subscribers' stations, a two-way electro-magnetic switch whereby selecting current may be thrown on or cut off of said line wires at said central station, a relay 20 operable from each of said subscribers' stations for actuating said switch in one direction cutting said selecting current on to said line wires, a second relay control having a contact whereby said selecting current may 25 be cut off from said line wires, and a third relay controlling a multiple stepping device, said third relay being adapted to take one step for each ground applied to said line wires after said second relay has been actuated.

8. In an intercommunicating telephone 30 lockout system the combination of a central station, multiple subscribers' stations, line wires connecting said central station and said subscribers' stations, a ground connection at said central station and each of said 35 subscribers' stations, a timer at said central station adapted to restore said intercommunicating telephone lockout system to nor-

mal conditions at predetermined times under various circuit conditions, and means controlled by the number of grounds applied at said subscribers' stations for determining at which one of said predetermined periods 40 said normal conditions of the system will be 45 restored.

9. In an intercommunicating telephone 50 lockout system the combination of a central station, multiple subscribers' stations, line wires connecting said central and said subscribers' stations, a ground connection at said central station and at each of said subscribers' stations, a timer at said central station, means associated with said timer whereby said system may be restored to normal 55 when one party has been called and does not answer within a predetermined time, and additional means associated with said timer for preventing the restoring to normal condition of said system at said predetermined 60 time if more than one party is called.

10. In an intercommunicating telephone 65 lockout system the combination of a central station, multiple subscribers' stations, a pair of line wires connecting said central station and said subscribers' stations, a ground connection at said central station and each of said subscribers' stations, synchronously operated wheels at said central station and said subscribers' stations, means for applying selecting current to said line wires at 70 said central station, operable from each of said subscribers' stations, and means associated with the synchronous wheel at said central station for cutting off said selecting 75 current from said line wires.
